Primary Examiner — Ricky Pham(74) *Attorney, Agent, or Firm* — Adler Pollock & Sheehan P.C.(57) **CLAIM**

The ornamental design for a steamer plate, as shown and described.

DESCRIPTION

FIG. 1 is a perspective view of a steamer plate in accordance with the subject disclosure.

FIG. 2 is a top view thereof.

FIG. 3 is a bottom view thereof.

FIG. 4 is a front view thereof, with the top of the plate facing to the right.

FIG. 5 is a left side view thereof, with the top of the plate facing to the left.

FIG. 6 is a right side view thereof, with the top of the plate facing downward; and,

FIG. 7 is a rear view thereof, with the top of the plate facing up.

The broken line showings are included for the purpose of illustrating portions of the invention and form no part of the claimed design.

1 Claim, 7 Drawing Sheets(56)
